(57) **CLAIM**

The ornamental design for a support system for a computer cart, as shown and described.

DESCRIPTION

FIG. 1 is a front perspective view of a support system for a computer cart embodying our novel design shown in context on an example computer cart;

FIG. 2 is a front view of the support system for a computer cart of FIG. 1 also shown in context on an example computer cart;

FIG. 3 is a left side view of the support system for a computer cart of FIG. 1 also shown in context on an example computer cart;

FIG. 4 is an enlarged front perspective view of a support system for a computer cart of FIG. 1;

FIG. 5 is a front view of the support system for a computer cart of FIG. 4, the back side being the same as the front;

FIG. 6 is a left side view of the support system for a computer cart of FIG. 4, the right side view being the same as the left side view;

FIG. 7 is a top plan view of the support system for a computer cart of FIG. 1; and,

FIG. 8 is a bottom plan view of the support system for a computer cart of FIG. 1.

The broken lines shown in the drawings are for illustrative purposes only and form no part of the claimed design.
